UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

RAILWAY CAR.

Application filed January 7, 1926. Serial No. 79,782.

My invention relates to railway cars and particularly to the framing of freight car superstructure. Some of the details of my invention are especially adapted for hopper car structure, although my invention may be utilized in other car framing as well as in hopper cars.

The objects of my invention are to provide a maximum capacity for cars of the type described; to provide improved connections between posts and side chords and between side and end walls and between side and floor walls and the underframe structure.

Other special objects of my invention will be referred to in the description of the detailed structure.

In the accompanying drawings which illustrate a selected embodiment of my invention—

Figure 1 is in part a top view of a hopper car embodying my invention and in part a horizontal section taken approximately on line 1—1 of Figure 2.

Figure 2 is in part a side elevation of a car and in part a vertical longitudinal section along the center line of the car.

Figure 3 is a transverse vertical section through one-half of the car.

Figure 4 is an end elevation of the car.

Figure 5 is a top view of one corner of the car drawn on an enlarged scale.

Figure 6 is a vertical section taken on line 6—6 of Figure 5.

Figure 7 is a vertical transverse section taken on line 7—7 of Figure 5.

Figure 8 is a detail illustrating the corner portion of the end floor sheet.

Figure 9 is a detail of the side wall stiffening construction, taken on line 9—9 of Figure 1.

The car underframe illustrated forms the subject-matter of my copending application Serial No. 76,479, filed December 19, 1925, and is mounted near its four corners upon trucks of the general type described in Patent No. 995,560, issued to H. M. Pflager June 30, 1911, and more particularly described and claimed in the copending Pflager application Serial No. 34,706 filed June 3, 1925, which type of truck permits the location of the truck very close to the end of the underframe and permits the location of the hopper floor very close to the wheels of

the truck and therefore close to the end of the underframe. It is always desirable in hopper car construction to obtain maximum capacity for a given length and in some classes of service the length of the car is limited by the spacing of storage bins or other equipment into which a trainload of cars must discharge or with which the cars must otherwise cooperate. Hence the location of the end floors as close as possible to the end of the car is especially desirable in such cases and each structural feature or relationship of parts which contributes to such an arrangement or otherwise increases the car capacity, constitutes a real improvement. In my present disclosure a number of details helping to secure the above described result are described and I consider all such as parts of my invention.

The main portion of my car body comprises inclined end floors A, inclined side floors B, and vertical side walls C, the space between the lower ends of the inclined floors A and B being provided with hinged doors D, the structure and mounting of which forms the subject-matter of my copending application Serial No. 67,828, filed November 9, 1925.

The end floor A is shown as consisting of three plates, a flat central plate 1, and curved and flat plates 2 which are located at each side of the central plate 1. Plates 2 curve toward the sides of the car and the longitudinal center thereof and are preferably arranged so that the arc of their curvature is tangent to plate 1, thus avoiding the provision of an angle at the joints between plates 1 and 2. Along a line x spaced substantially from plate 1, each plate 2 is flattened and bent outwardly toward the side of the car and inwardly toward the longitudinal center of the car as indicated at 2^a . The outer edge y of the bent portion 2^a extends upwardly and outwardly in a straight line from the lower edge of inclined side floor B to a point about halfway up the vertical side wall C and the remainder of plate 2 is shaped and bent to form a triangular break portion 2^b extending at an angle to portion 2^a outwardly and inwardly toward the center of the car to meet vertical side wall C and inclined side floor B, the outer edge of portion 2^b being flanged as indicated at 2^c to parallel the side floor and

wall and through which rivets secure the end floor to the side floor and wall.

The flat central plate 1 extends upwardly and outwardly to a line approximately above 5 the striking face of the end sill E and is there provided with a top chord angle 3, one flange of which is disposed horizontally and the other flange of which is inclined 10 downwardly and rearwardly to be secured along the upper edge of plate 1 and the upper edges of adjacent plates 2, including the upper edges of sections 2^a. The horizontal flange of end top chord 3 forms an end platform projecting beyond the end sill of the 15 car for a limited distance on each side of the longitudinal center line of the car, as permitted by the Federal Safety Appliance rules, and on each side of this platform forming portion the end top chord is inclined toward 20 the side of the car and inwardly toward the longitudinal center of the car to provide the necessary clearance between the ends of the tops of the car sides on adjacent cars.

Four side or corner posts 4 are located at 25 the points indicated and extend upwardly from the underframe to the top of the car side. Each of these posts 4 is of Z-bar cross section with its web extending transversely of the car side wall and with its outer flange 25 extending toward the center of the car and its inner flange extending toward the end of the car. The car side walls C are mounted upon the outer flanges of these posts and supplemental side wall plates 5 are secured 35 to the inner flanges of these posts (see Figures 5, 6 and 7). It will be noted that these supplementary side walls are spaced inwardly from the outer side of the car to leave a space adjacent the end of the car for 40 clearance around the side ladder rungs 6.

Near the top of post 4 the flanges of the latter are bent upwardly and inwardly toward the center of the posts, the outer flange 7 extending vertically upwardly to very near 45 the top of the post and then being bent inwardly and upwardly at an angle of about forty-five degrees. The inner flange 8 of the post starts to incline upwardly and inwardly a substantial distance below the top of the 50 post and terminates at approximately the same point as the outer flange 7.

A side top chord 9, preferably consisting of a bulb angle, is carried on the top of posts 4 and the other side posts of the car. This 55 angle is disposed as shown so that its lower flange rests upon the inclined portion of post flange 7 and its upper flange is inclined at a slight angle to the inclined portion of post flange 8.

The plate 5 supplements the end portion 60 of the side wall and extends over the inclined portion of post flange 8 and the upper flange of top chord 9. This inclination of plate 5 increases the car capacity over an arrangement in which a corresponding plate and the

inner flange of the post would extend vertically to the top of the car. My arrangement also facilitates the downward discharge of the load from its outermost point. The outer end of plate 5 is vertical and provides 70 a support for the upper end of the ladder post 6^a.

A novel pressed or cast gusset provides a rigid diagonal connection between the side wall and end floor of the car without reducing the car capacity. It includes a horizontal flange 10, overlying the horizontal flange of the end top chord 3, a substantially channel-shaped portion 11 overlying the upper portion of plate 5 and side top chord 9, and an inwardly and downwardly inclined portion 12 which extends across the angle between the end floor and supplemental plate 5. This gusset securely ties chords 3 and 9 to each other and forms a channel-like reinforcement for the side of the car corner, the inclinations of the various portions of the gusset at angles to each other serving to substantially increase its resistance to any distortion. With this corner 90 construction, the full value of the end portion of the top chord 9 is unnecessary and the lower flange of the same may be cut away partly as indicated at 9^a to provide clearance around the adjacent top ladder rung 9^b 6 which is secured at one end to the upper flange of chord 6 and at the other end to the ladder post 6.

The upper portions of the car side wall plates C are inclined inwardly over the lower flange of side top chord 9. At posts 4 and at other selected points along the side of the car the flanges of chord 9 are braced by suitable fillers 13. The lower portion of side walls B are crimped at 31 throughout the 105 length of the side floor to fit over the same and be riveted thereto, thereby eliminating any upwardly facing crevice which might receive moisture and dirt with objectionable results.

An additional feature of the meeting of the end floor and car side structure is the provision of a flange 14 along the upper portion of the edge of section 2^a of the end floor. This flange is riveted to supplemental plate 5 and post flange 8. At the lower end of flange 14 another short flange 14^a is formed from the edge of section 2^a. This flange is bent at such an angle to the remainder of the end floor plate that it is parallel with and juxtaposed with the web of post 4 and is riveted thereto.

Another feature of my improved superstructure is the supporting of the inclined side floor B and the side wall C upon the car underframe. In Figure 3 the side member of the underframe is shown in section and includes a main vertical flange 15, a horizontal top flange 16 extending inwardly from flange 15, and a shallow vertical flange 130

17 extending downwardly from the inner end of flange 16. Resting on flange 16 is a triangular member extending upwardly and outwardly from the underframe member and 5 having a flange 18 extending along the inclined side floor B, a flange 19 extending from the outer end of flange 18 to the top of flange 16, and a base flange 20 connecting the lower ends of flanges 18 and 19. This 10 floor supporting member includes a web 21 extending between flanges 18, 19, and 20 and this web is reinforced by a cross flange 22. A vertical flange 28 extends downwardly from the outer end of flange 20 and is secured to the underframe vertical flange 15. Projecting outwardly from flanges 19 and 28 is a web 23 terminating in a flange 33 which forms a continuation of flange 22 and extends downwardly within the outside line 15 of the car and inwardly to engage the lower portion of flange 28. An enlargement 19^a on flange 19 affords support for a pipe bracket 24 and the web 21 may be provided with openings 25 to receive brake rods, door 20 operating apparatus, or air brake or other piping. A suitable horizontal flange 25^a affords an extended bearing for such accessories. Preferably the floor supporting member just described will consist of a one-piece casting, although pressings or structural members may be interconnected to provide a similar support.

The side structure is further braced by triangular stiffeners 26, the inner edges of 35 which extend from near the lower edge of the side floor to the top side chord. These stiffeners are connected to the side wall and floor and to the triangular supporting member just described by means of angles 27. 40 Both flanges of each angle 27 are bent inwardly at their upper ends to underlie the lower flange of top chord 9 and preferably the angles 27 are riveted to the top chord. Between stiffeners 26 and the end of the car 45 I provide another stiffening member 29 comprising a pressing or casting of V-shaped cross section and tapering from top to bottom and having flanged legs for attachment to the side wall. These flanges are bent inwardly at their upper end to underlie chord 9 and be secured thereto. I show fillers 13 in 50 vertical alignment with stiffeners 29, the same providing a continuous post-like structure, parts of which are on different sides of the side wall. This result may be also accomplished by placing two angles back to back, fastening them together and to the side wall. The tops to be bent inwardly as described for angles 27.

60 The straight horizontal lower end of the central part of the inclined end floor is spaced above the inner portions of the laterally inclined dumping doors, and to close the gap between these parts I provide a 65 plate 30 attached to the underside of the ad-

jacent underframe element and bent downwardly from the lower edge of the end floor.

As door D is inclined and crosses the horizontal plane of the lower edge of the end floor, it is unnecessary for plate 30 to extend more than partway across the end of the floor. As the rear or hinged side of the door is above the level of the bottom of the inclined floor, another gap is there produced between each floor and door. This gap is closed by the vertical web of the end door-stiffening member 32. This enables me to make the lower edge of the end floor and the corresponding portion of the underframe 75 straight and horizontal which is an economical and otherwise desirable construction.

Each Z-bar corner post 4 is mounted on the end of an underframe side member 15 which terminates a substantial distance from the 80 end of the car and is connected at its end to the adjacent draft sill 34 by a transverse member 35. This construction ties the superstructure and draft sills together and increases the rigidity of the car, at the same 85 time unnecessary weight is eliminated by the shortening of the car side sills.

Obviously, many of the details of my improved car structure may be varied without departing from the spirit of my invention as 90 set forth more particularly in the appended claims. I contemplate the exclusive use of all such variations as may be made in the commercial development of my car and as are included in the scope of my claims. 100

I claim:

1. In a hopper car having a discharge opening, an inclined end floor comprising a flat central section, and curved sections tangent to said central section and extending outwardly therefrom toward the side of the car and inwardly toward the longitudinal center of the car, said sections extending from said opening to the end top chord of the car body. 105

2. In a hopper car, a car side wall and side floor, an end floor comprising a flat central section, a section on each side of said central section curved toward the side of the car and toward the longitudinal center of the car, and flat sections on the sides of said 115 curved sections extending toward the side of the car and toward the longitudinal center of the car and connected to said side wall and side floor. 120

3. In a hopper car, an end sill, an inclined end floor, the central section of which extends in a straight line across the car and the adjacent sections of which are inclined toward the sides and the longitudinal center of the car, a top chord on said end floor, the central portion of which extends in a straight line above said end sill and forms an end platform. 125

4. In a hopper car, a flanged side top 130

- chord, a flanged end top chord, the upper flanges on said chords extending outwardly of the car, and a gusset secured to said flanges to connect said chords to each other at points spaced from their ends, said gusset extending downwardly and inwardly of the car in the angle between said chords.
5. In a hopper car, a side top chord having an upper flange extending outwardly and upwardly, an end top chord having an upper flange extending outwardly, a gusset having its body inclined downwardly and inwardly and having a flanged upper portion secured to said chord upper flanges.
- 10 6. In a car, a side post with its inner face inclined outwardly and upwardly, a top side chord carried by said post, a top end chord, and a gusset secured to said chords and to said post face.
- 20 7. In a car, a post, a top chord carried thereby, a top chord disposed at an angle to said first mentioned chord, and a gusset connected to said post and chords and extending diagonally across the angle between said chords, the diagonal portion of said gusset being depressed below the level of its chord engaging portions.
- 30 8. In a car, an end top chord, a side top chord, a body post spaced from the end of said end top chord, and a corner gusset connected to said chords and posts, the diagonal portion of said gusset being depressed below the level of its chord engaging portions.
- 35 9. In a car, a body end structure, a Z-bar side post with its web extending transversely of the car and with the upper portion of its inner flange inclined upwardly and outwardly, a top chord carried by said post with an upper flange similarly inclined, and a corner gusset having a portion secured to said inclined flanges and a portion secured to said end structure, and a portion extending across the angle between the car side and end.
- 45 10. In a car, a post including a web, extending transversely of the car wall, and an inner flange, the upper portion of which is inclined outwardly and upwardly, an angular top side chord carried by said post and having a flange arranged at an angle to the horizontal and terminating adjacent the upper end of said post flange, and a connecting plate secured to the said flanges of said post and chord.
- 50 11. In a car, a post having inner and outer flanges, a flanged top chord, the width of which transversely of the car is less than the corresponding width of said post, said post being tapered longitudinally near its upper end to approximately the width of said chord, and respective plates secured to said post flanges and to said chord flanges.
- 60 12. In a car, a post having inner and outer flanges, a top chord carried by said post and having flanges disposed at an angle to each other, and individual plates connecting each flange of said post with a respective flange of said chord.
- 65 13. In a car, a post comprising a web with inner and outer flanges, the upper portion of which flanges are inclined upwardly and toward the center of the post, a top chord carried by said post, and load retaining plates secured respectively to said flanges and said chord. 70
- 75 14. In a car, a post having inner and outer flanges which are inclined upwardly and toward the center of the post, a top chord angle carried by said post with its flanges inclined to the horizontal, an outer wall secured to said post with its upper portion bent over and secured to one of said chord flanges, and a supplementary side plate secured to said post with its upper portion bent over and secured to the other 80 of said chord flanges.
- 80 15. In a car, a top chord angle having its flanges inclined to the horizontal and vertical, a post carrying said angle, and members separately connecting inner and outer faces of said post to respective flanges of said angle. 85
- 85 16. In a car, a side post of Z-bar cross section, the upper portion of the outer flanger of which is inclined inwardly toward the center line of the post, a top chord of angle cross section carried by said post with one flange resting on said post flange, the other flange of which chord is connected to the inner flange of said post. 90
- 95 17. In a hopper car, a side post of Z-bar cross section, the upper portion of the outer flange of which is inclined inwardly toward the center line of the post, a top chord of angle cross section, the width of which transversely of the car is substantially less than the corresponding width of said post side chord, resting on said post flange with the outer extensions of said chord and post in substantial vertical alignment. 100
- 105 18. In a hopper car, a side wall and floor, a corner post, an inclined end floor sheet, the outer side edge of which extends from in back of the lower portion of the inner face of said post to in front of the upper portion of the inner face of said post and the portion of said edge adjacent said post being flanged vertically to be secured to said post. 110
- 115 19. In a hopper car, a side wall and floor, a corner post having a web extending transversely of the car side wall, an inclined end floor sheet, the outer side edge of which extends from in back of the lower portion of the inner face of said post to in front of the upper portion of the inner face of said post and the portion of said edge adjacent said post being flanged vertically to be secured to said post web. 120
- 125 20. In a car, a side sill, an inclined side 130

- floor, and a member extending upwardly and outwardly from the top and side of said sill to support said floor.
21. In a car, a side sill, an inclined side floor, and a member resting upon said sill and comprising a web and a flange extending upwardly and outwardly from the inner upper edge of said sill, another flange extending upwardly and outwardly from the outer upper edge of said sill, and another flange extending outwardly and upwardly from the outer side of said sill below its upper edge, the outer portions of said flanges being united and serving to distribute the load on said floor inwardly and downwardly to said sill.
22. In a car, a side sill, an inclined side floor, and a member resting upon said sill and including a brace extending from a point adjacent the upper outer portion of said member to the outer face of said sill below the top thereof.
23. In a car, a side sill, an inclined side floor, and a one-piece casting including a triangular body resting on said sill and supporting said floor, a flange traversing said body near its outer end, and a portion extending downwardly and inwardly from said body near the outer end of said flange to brace said body from the lower portion of said sill.
24. In a car, a side sill, a side wall located above and outside of said sill, and inclined supports for said wall extending upwardly and outwardly from said sill.
25. In a hopper car, a side sill, a side floor extending upwardly and outwardly from said sill, a casting supporting said floor from said sill and including a web having reinforcing flanges, one of which is enlarged intermediate its ends, and a U-bolt pipe carrying bracket mounted on said enlargement.
26. In a hopper car, a side sill, an inclined floor above said sill, and a triangular support for said floor carried on said sill including a web extending transversely of the car having an opening for the passage therethrough of car accessories, and a horizontally extending flange on said web adjacent said opening for supporting such accessories.
27. In a hopper car, a dumping door opening, an upwardly inclined side floor with an end of its lower edge aligned with an end of said opening, an upwardly inclined end floor with a side of its lower edge aligned with a side of said opening, and corner break portions connecting said side and end floors and forming a dihedral angle with each of said floors.
28. In a car, a vertical side wall, the upper edge of which is flanged inwardly and upwardly, and a stiffening member for said side wall having a depth at its upper end corresponding to the inward extension of said edge and tapering downwardly to the base of the side wall.
29. In a car, a vertical side wall, the upper edge of which is flanged inwardly and upwardly, and a stiffening member for said side wall U-shaped in cross section with its legs flanged and secured to said side wall and with its body tapering from its upper end to its lower end.
30. In a car, a vertical side wall, the upper edge of which is flanged inwardly and upwardly, an outwardly facing angular top chord carried by said flanged portion, a filler between the flanges of said chord, and an elongated stiffener on the inner face of said side wall vertically aligned with said filler, said filler and stiffener being connected through said angle and side wall flange and forming a continuous reinforcing post for stiffening said wall and supporting said chord.
31. In a car, a vertical side wall, the upper edge of which is flanged inwardly and upwardly, an outwardly facing angular top chord carried by said flanged portion, fillers between the flanges of said chord, and side wall stiffeners extending downwardly from the lower flange of said chord.
32. In a hopper car, a car end wall of convex shape comprising a flat central section, a curved section on each side of said central section, a second flat section at the outer edge of each curved section, and a third flat section at the outer edge of each of said second-mentioned flat sections, said latter-mentioned flat sections forming load supporting surfaces breaking the corners of the car.
33. In a hopper car, a dumping door opening, an upwardly inclined side floor with an end of its lower edge aligned with an end of said opening, and a wedge shaped corner break portion with its apex at the corner of said opening, said portion extending diagonally upwardly from said corner and forming a dihedral angle with each of said floors.
34. In a hopper car, a side wall, an inclined end floor, and a channel-shaped gusset extending across the corner between the top chords of said wall and floor and forming a diagonal brace for the latter.
35. In a hopper car, an end floor, a vertical side wall, a supplementary vertical member forming an offset end of the upper portion of said side wall adjacent said end floor, and a member forming a break in the corner of said side wall and end floor, said break member extending downwardly from the lower part of said supplementary member.
36. In a hopper car, an underframe terminating in an end sill, an inclined end floor, the upper edge of which is located substantially above said end sill, and a top chord angle member having one flange disposed

horizontally and projecting outwardly beyond the face of the end sill.

37. In a car, a side wall, a top chord including an outwardly projecting flange, a side ladder rung adjacent the end and top of said wall, said flange being cut away adjacent said rung to provide clearance about said rung.

38. In a car, a post, a top chord angle carried by said post with its flanges inclined to the horizontal, an outer wall secured to said post with its upper portion bent over and secured to one of said chord flanges, and a supplementary side plate secured to said post with its upper portion bent over and secured to the other of said chord flanges.

39. In a car, a side wall, a top chord including a flange inclined inwardly from said side wall, side wall stiffeners including angle members each having the upper ends of both of its flanges bent inwardly beneath said chord flange.

40. In a hopper car, an end floor sloping upwardly toward the end of the car and having a straight horizontal lower edge, a dumping door sloping upwardly toward the side of the car with its front edge extending below the level of said floor, and a plate forming a downwardly projecting vertical extension of said floor enclosing the gap between said floor and the front portion of the end of said door.

41. In a hopper car, an end floor sloping upwardly toward the end of the car and having a straight horizontal lower edge, a dumping door sloping upwardly toward the side of the car with its end extending above and below the level of the lower edge of said floor, and means on said floor and door for closing the gaps between them at their adjacent edges.

42. In a hopper car, a side wall, an inclined end floor, a corner post for said wall

adjacent said floor but located inwardly of the car from the upper end of said floor and having its inner face inclined upwardly and outwardly, a plate supplementing said side wall and secured to said post face and extending from said post toward the end of the car, and a ladder rung carrying post secured at its upper end to said plate.

43. In a car, a post having inner and outer flanges which are inclined upwardly and toward the center of the post, a top chord angle carried by said post with its flange inclined to the horizontal, a corner gusset plate connected to the end of said chord, an outer wall secured to said post, and a supplementary side plate secured to said post with its upper portion secured to said gusset and to one of the flanges of said chord angle.

44. In a hopper car, an end sill, an inclined end floor, the upper edge of which is located substantially above said end sill, and a top chord angle having one flange disposed horizontally and, intermediate its ends, projecting beyond the face of the end sill and beyond said intermediate portion extending inwardly and outwardly to the car side.

45. In a hopper car, a draft sill, a side sill terminating short of the end of the car, a transverse connection between the end of said side sill and said draft sill, and a body corner post mounted on the end of said side sill at the point of junction with said connection.

46. In a hopper car, an underframe terminating in a striking face, an inclined end floor, the upper edge of which is located as far from the longitudinal center of the car as said striking face, and a top chord member on said edge forming an end platform.

In testimony whereof I hereunto affix my signature this 31st day of December, 1925.

WILLIAM M. SHEEHAN.
